UNITED STATES PATENT OFFICE.

JAMES W. MILLER, OF NEWARK, ASSIGNOR OF ONE-HALF TO ISAAC M. MILLER, OF EAST ORANGE, NEW JERSEY.

DESIGN FOR A SLEEVE-BUTTON.

SPECIFICATION forming part of Design No. 12,482, dated September 20, 1881.

Application filed February 21, 1881. Term of patent 14 years.

To all whom it may concern:

Be it known that I, JAMES W. MILLER, of the city of Newark, county of Essex, and State of New Jersey, have invented and produced a new and original Design for Sleeve-Buttons, Lockets, and Similar Articles of Jewelry, which design is fully set forth in the following specification.

The button or other article upon which the design is to be used may be of any ordinary or suitable material, such as gold, silver, celluloid, hard rubber, and the like. Upon the face of the button or other article is an initial letter or letters, which are generally formed separately and applied to the face of the article; but they may be produced by embossing, so that they shall stand out *in rilievo*, or they may be countersunk, or the outlines determined by mere engraving. The letters themselves may be of any pattern, plain or ornamental, simple initial letters, or several letters interlaced monogrammatically, or placed side by side, as may be desired. Within the contour or outline of the letter or letters are formed, by engraving, etching, or otherwise, landscapes or water views, and these views may be varied indefinitely or modified as to detail, as will be hereinafter more fully set forth.

The said design will now be described in connection with the accompanying drawings, which form a part of this specification, and in which—

Figures 1 and 2 are top views of a sleeve-button or similar article, illustrating the design upon the face thereof; and Fig. 3, a sectional view, showing the formation of the initial letter *in rilievo*.

On the face of the letter shown in Fig. 1 is a view representing earth in the foreground, with water in the distance and sky overhead. By using different-colored metals, as gold and silver, or the various alloys of gold, for the different portions of the field, a more striking effect may be produced. The representation of a plant is in the foreground of the picture. This may be replaced by the figure of a bird, as in Fig. 2, or other appropriate object, and the scene may be made more realistic by the representation of a sail upon the water in the distance and of birds flying overhead, as shown in the figure.

Fig. 2 represents a somewhat different scene,

and serves to show how the design may be varied without departing from the spirit of the invention. The landscape or water view, as well as the various details thereof, may be further varied as the fancy may suggest or to suit the outline of the particular initial letter or letters upon which they are to be produced.

The buttons or other articles upon which the design is used may be of precious metals or of other substances from which such articles are commonly made. Where the precious metals are employed the effects of earth, sky, and water may be produced, as already explained, by the use of metals of different hue or by oxidation. The effect may be still further heightened by using in connection with the engraving enamel of various colors, whereby perfect pictures of landscapes and accompanying figures can be produced.

It will be understood that hard-rubber or celluloid jewelry could be similarly ornamented, and the faces of the letters on such jewelry may be gilded or inlaid with precious metals; or the design may be produced in colors in any ordinary or suitable way.

The invention therefore is not confined to the use of any particular material, nor to the particular landscapes or views shown in the drawings, but includes the ornamentation of sleeve-buttons, lockets, or similar articles of jewelry by an initial letter or letters engraved, raised, embossed, or otherwise formed thereon, and having within the outlines of such letter or letters a land or water view, with appropriate figures or objects in the different portions of the field, and whether or not colored effects are given to such landscape or water view.

I claim—

A design for sleeve-buttons, lockets, and similar articles of jewelry, consisting in an initial letter or letters raised, stamped, engraved, or otherwise suitably produced thereon, said letter or letters being ornamented with views, substantially as shown and described.

In testimony whereof I have signed this specification in the presence of two subscribing witnesses.

JAMES W. MILLER.
